UNITED STATES PATENT OFFICE.

CARL J. VELEY AND LINCOLN S. DEAL, OF KALAMAZOO, MICHIGAN, ASSIGNEES TO
COMSTOCK AUTOMATIC PUMP COMPANY, OF COMSTOCK, MICHIGAN, A CORPORATION.

PUMP.

1,159,554.

Specification of Letters Patent.

Patented Nov. 9, 1915.

Application filed April 15, 1914. Serial No. 831,900.

To all whom it may concern:

Be it known that we, CARL J. VELEY and LINCOLN S. DEAL, citizens of the United States, residing at Kalamazoo, Michigan, have invented certain new and useful Improvements in Pumps, of which the following is a specification.

This invention relates to improvements in pumps.

10 The main objects of this invention are: First, to provide an improved pump which is especially desirable for use in pressure systems. Second, to provide in a motor pump an improved pumping jack. Third, to 15 provide an improved motor pump structure adapted for pumping both hard and soft water which is automatic in its operation. Fourth, to provide an improved pump which is very quiet in its operation. Fifth, to provide an improved motor pump in which the driving connections are so arranged that the strains are balanced and friction minimized. Sixth, to provide an improved motor pump which is very compact and is 25 comparatively simple and economical in structure.

Further objects, and objects relating to structural details, will definitely appear from the detailed description to follow.

30 We accomplish the objects of our invention by the devices and means described in the following specification.

The invention is clearly defined and pointed out in the claims.

35 A structure which is a preferred embodiment of our invention is clearly illustrated in the accompanying drawing forming a part of this specification, in which:

Figure I is a rear perspective view of a 40 structure embodying the features of our invention. Fig. II is a horizontal section on a line corresponding to line 2—2 of Fig. I. Fig. III is an enlarged detail horizontal section on a line corresponding to line 3—3 45 of Fig. VI, showing details of the lubricating means and of the jack mounting. Fig. IV is a detail vertical section on a line corresponding to line 4—4 of Fig. II, showing further details of the lubricating means. Fig. V is a detail vertical section on a line 50 corresponding to line 5—5 of Fig. II. Fig. VI is a detail section on a line corresponding to line 6—6 of Fig. III, showing further details of the lubricating means. Fig.

VII is a detail vertical section on a line 55 corresponding to line 7—7 of Fig. V, showing details of the support for the shaft 80. Fig. VIII is a central horizontal section through the cross head 8. Fig. IX is a horizontal section on a line corresponding to 60 line 9—9 of Fig. I, showing details of the soft water pump supporting brackets. Fig. X is an enlarged detail vertical section through the pump cylinders 1 and 5 on a line corresponding to line 10—10 of Fig. I. 65 Fig. XI is a horizontal section on a line corresponding to line 11—11 of Fig. X, showing details of the cylinder 5 and its piston. Fig. XII is a detail vertical section on a line corresponding to line 12—12 of Fig. 70 XI. Fig. XIII is a perspective view of the valve 9 of the piston 6. Fig. XIV is a central vertical section through the soft water pump cylinder and piston. Fig. XV is a diagrammatic view showing the connections 75 for the pump to the tanks and the automatic controlling means for the motor, the parts being represented in conventional form. Fig. XVI is an enlarged detail vertical section through the valve 58.

In the drawing similar reference characters refer to similar parts throughout the several views, and the sectional views are taken looking in the direction of the little arrows at the ends of the section lines.

Referring to the drawing, the pump cylinder 1 is arranged within the well and is shown, as is quite common practice, as a portion of the well pipe. The plunger 2 of this cylinder 1 is provided with a ball check 90 valve 3. A check valve 4 is provided below the plunger 2. On the upper end of the well pipe is a cylinder 5. The cylinder 5 is of larger area than the cylinder 1, the object of which will appear later. A piston 6 is provided for the cylinder 5.

The piston 6 is connected to the plunger 2 by means of the pump rod 7 so that the plunger and piston reciprocate together. The pump rod 7 is extended through the top 100 of the cylinder 5 and connected to the cross head 8. The piston 6 is provided with a downwardly opening check valve 9 which opens on the upstroke of the piston and closes on its downstroke, being held yielding 105 on its seat by means of the spring 10.

The upper end of the cylinder 5 is provided with an air inlet valve 11 which is

opened by the downstroke of the piston 6 to admit air to the cylinder 5 above the piston. This valve is closed on the upstroke of the piston so that the air passes through the valve 9 into the cylinder below the piston. The valve 11 is held yieldingly on its seat by means of the coiled spring 12. A vent cock 13 is provided for the upper end of the cylinder. When this vent cock is opened air enters and passes from the cylinder above the piston as the piston reciprocates. The cylinder 5 is connected to the storage reservoir 14 by means of the pipe 15, the tank and connections being shown in conventional form in Fig. XV.

The pipe 15 is provided with a check valve 16. On the upstroke, water is lifted by the plunger 2 into the cylinder 5, and since the cylinder 5 is of greater diameter than the cylinder 1, air passes the valve 9. On the downstroke, the air and water is forced out of the cylinder 5 past the valve 16 into the tank 14. The air in the cylinder 5 below the piston serves as a cushion preventing shocks and noise as the pistons move downwardly. We thus secure a combined air and water pump which maintains the desired pressure in the tank 14.

The cross head 8 is mounted to reciprocate upon the front uprights 17 of the jack frame. The rear uprights 18 of the jack frame are supported by a suitable floor plate 19 having sockets 21 therein for the uprights. The uprights 17 and 18 are connected by the H-shaped horizontal frame members 22 having holes at the ends of their arms for the uprights. These uprights are preferably sections of pipe, as shown, and the frame members 22 are secured thereon by means of set screws 23.

The well pipe 26 serves as an anchor and support for the pump frame. The shafts for the driving and crank wheels are supported by a frame member 27 which constitutes the bottom horizontal frame member of the jack frame. The member 27 is secured to the well pipe 26 by means of a clamp comprising clamp members 28 and the clamping bolt 28'. The uprights 18 extend through the frame member 27, which is secured thereto by set screws 24. The crank wheel shaft 29 extends through the frame member 27, there being a crank wheel 30 on each end of the shaft. The pitman or connecting rods 31 are connected to the crank wheels by suitable crank or wrist pins 32. To regulate the stroke of the pump, the crank wheels are provided with a plurality of wrist pin bearings 33 positioned at different distances from the shaft.

The driving wheel 34 is connected to the crank wheels by means of the belts 35, the hub of the driving wheel being provided with pulleys or belt wheels 36 for these belts. Belt tighteners are provided for the

belts 35, the belt tighteners shown consisting of the pulleys 37 mounted on the swinging arms 38 which are yieldingly supported by the coiled springs 39.

The structure shown is driven by an electric motor shown conventionally at 40. The motor is connected to the driving wheel by means of the belt 41. The motor is supported on a bracket or table 42 mounted on the bottom horizontal frame member 22. This table 42 is supported at one side so that the motor pulley 43 is directly above the wheel 34. A belt tightener is provided for the belt 41, the belt tightener consisting of a pulley 44 carried by the forked arm 45 which is mounted on the shaft 80, as are the arms 38. By this arrangement of the parts described, we secure a very compact and simple structure.

The soft water pump cylinder 48 is supported by a pair of brackets extending between the uprights 17. These brackets consist of a pair of members 49 clamped together upon the pump cylinder 48 and the uprights by the bolts 50. The plunger 51 for the cylinder 48 is provided with a pump rod 52 which is connected to the cross head 8. Thus connected, the pumps are operated together. The cylinder 48 is connected to the soft water pressure or storage tank 53 by the pipe 54, see Fig. XV—and to the cistern or supply 55 by the pipe 56. The pipe 56 is provided with a check valve 57 shown conventionally only, the check valve being disposed between the supply and the connection of the pipe 54 to the cylinder 48. The pipe 54 is provided with a check valve 58 controlled by an electromagnet, the valve stem 59 constituting the armature of such electromagnet. See Fig. XVI. Air under pressure is supplied to the tank 53 through the pipe 60 connecting the tank 53 with the tank 14. A return check valve 61 is provided for the pipe 60.

The electric motor 40 is controlled by the switch 62 operated by the float 63 in the pressure tank 14, the switch 62 being opened by the rising of the float when the tank is substantially filled, thus stopping the motor, the switch being connected to the motor through the circuits 64. When the water within the tank 14 falls below a predetermined point, the float falls, closing the switch 62 and starting the motor. The plunger 51 is, of course, owing to its connection to the cross-head, operated whenever the cross head 8 is operated.

The soft water pump is rendered inoperative for pumping water by the opening of the valve 58 in the connection 54 for the reason that, when this valve is opened, the water travels from the cylinder 48 into the pipe 54 and back to the cylinder as the plunger reciprocates. The valve 58 is automatically held open by the electromagnet, 130

the delivery of current to the magnet being controlled by the float 65 in the tank 53 which operates the switch 66 of the circuit 67, the switch being open when the water 5 within the tank is below a predetermined point and closed when it is at this point. With the parts thus arranged, when the water fills the tank 53 to the desired point, the float operates to close the switch and the 10 electromagnet is thus operated to hold the valve 58 in its open position, thereby rendering the soft water pump inoperative as the water merely passes from the cylinder into the pipe 54 and vice versa. A safety 15 valve 68 is provided for the tank 53, the safety valve being automatically opened, allowing the air to escape, when the pressure within the tank exceeds a predetermined point. The water is drawn from the tanks 20 through the house systems 69 and 70, which are shown only in conventional form in Fig. XV. Where an alternating current is used the electromagnet is preferably supplied through the induction coil 71 connect- 25 ed to the motor circuits 64.

To lubricate the crank pins 32 and the crank wheels 30, the wheels are formed with oil chambers 75 which embrace the crank pins and also the ends of the shaft 29. The 30 shaft is formed hollow and provided with lubricant openings 76 communicating with the oil chamber 75. See Fig. III. The idle bearings 33 for the crank pins are closed by plugs 77 which prevent the escape of lubricant from the lubricant chamber 75. The oil is introduced through the shaft which is provided with an oil hole 78. See Figs. II and IV. By providing this lubricating means for the bearings, very little attention 10 is necessary. The driving wheel 34 is lubricated by providing its hub with a chamber 79 which is filled with a suitable absorbent material adapted to retain the lubricant. The shaft 80 is supported on the arms 81 of 15 the frame member 27, the arms having holes 82 therein for the shaft. See Fig. VII. Set screws 83 clamp the shaft against the spaced rest 84. Between the arms 81 and the ends of the hubs are thrust collars 85 20 which are flared at their inner ends as at 86. The ends of the hub of the driving wheel are chambered to receive the flared ends of these collars and provided with oil openings 87 connecting the chambers and the oil res- 25 ervoir. The chambers are expanded inwardly and the oil passages are disposed so that the centrifugal force tends to carry the lubricant back into the oil chamber 79.

Our improved pump is automatic in its 30 operation, and is substantially noiseless and without vibration, which is a feature of very great advantage as it is especially designed for use in residences although ad- 35 vantageous for use elsewhere. The pressure is automatically maintained,—that is, air

and water are simultaneously pumped if de- 70 sired—so that the water is under pressure and may be delivered to any part of a house system as desired.

We have illustrated and described our im- 75 proved pump in a practical embodiment. We have not attempted to illustrate or de- 80 scribe various modifications which we con- 85 template, as we believe the disclosure made will enable those skilled in the art to which this invention relates, to embody or adapt the same as may be desired to meet the par- 90 ticular conditions. We desire, however, to be understood as claiming our improvements specifically in the form illustrated as well as 95 broadly within the scope of the appended 100 claims.

Having thus described our invention what 105 we claim as new and desire to secure by Letters Patent is:

1. In a structure of the class described, the combination of a pair of pressure stor- 110 age tanks, the tops of the tanks being con- 115 nected by an air passage, said tanks being provided with a pressure relief valve; a 120 pump comprising connected cylinders dis- 125 posed one above the other, the upper cylin- 130 der being of greater diameter than the lower, the lower cylinder being provided with an inlet check valve, the upper cylin- 135 der being provided with an air inlet valve and a vent cock at its upper end, there being a delivery connection provided with a re- 140 turn check valve for the lower end of the upper cylinder to the first tank; a plun- 145 ger for the lower cylinder; a piston for the upper cylinder provided with a spring check valve permitting the passage of air below the piston on its upstroke, said piston and plunger being connected to move together, 150 whereby on the upstroke water is lifted 155 into the upper cylinder and air passes be- 160 low its piston and on the downstroke air and water are forced into the first tank; a second 165 pump, there being a return check valve in 170 the supply connection for the second pump and a delivery connection for said second 175 pump to the second tank provided with a 180 return check valve; an electro-magnet for holding said return check valve in said sec- 185 ond tank connection in its open position; a 190 float controlled switch for said electro-mag- 195 net actuated to close when the water in the 200 second tank is at a predetermined point; and a float controlled motor switch actuated to open when the water in the first tank 205 is at a predetermined point.

2. In a structure of the class described, the combination of a pair of pressure stor- 210 age tanks, the tops of the tanks being con- 215 nected by an air passage, said tanks being provided with a pressure relief valve; a 220 pump comprising connected cylinders dis- 225 posed one above the other, the upper cylin- 230 der being of greater diameter than the lower,

lower, the lower cylinder being provided with an inlet check valve, there being a delivery connection provided with a return check valve for the lower end of the upper cylinder to the first tank; a plunger for the lower cylinder; a piston for the upper cylinder, there being means for delivering air below the piston on its upstroke, said piston and plunger being connected to move together, whereby on the upstroke water is lifted into the upper cylinder and air passes below its piston and on the downstroke air and water are forced into the first tank; a second pump, there being a return check valve in the supply connection for the second pump and a delivery connection for said second pump to the second tank provided with a return check valve; an electro-magnet for holding said return check valve in said second tank connection in its open position; a float controlled switch for said electro-magnet actuated to close when the water in the second tank is at a predetermined point, and a float controlled motor switch actuated to open when the water in the first tank is at a predetermined point.

3. In a structure of the class described, the combination of a pair of pressure storage tanks, the tops of the tanks being connected by an air passage, said tanks being provided with a pressure relief valve; a pump comprising connected cylinders disposed one above the other, the upper cylinder being of greater diameter than the lower, the lower cylinder being provided with an inlet check valve, the upper cylinder being provided with an air inlet valve and a vent cock at its upper end, there being a delivery connection provided with a return check valve for the lower end of the upper cylinder to the first tank; a plunger for the lower cylinder; a piston for the upper cylinder provided with a spring check valve permitting the passage of air below the piston on its upstroke, said piston and plunger being connected to move together, whereby on the upstroke water is lifted into the upper cylinder and air passes below its piston, and on the downstroke air and water are forced into the first tank; a second pump, there being a delivery connection for said second pump to the second tank provided with a return check valve; means for automatically controlling said return check in said connection; and a float controlled motor switch actuated to open when the water in the first tank is at a predetermined point.

4. In a structure of the class described, the combination of a pair of pressure storage tanks, the tops of the tanks being connected by an air passage, said tanks being provided with a pressure relief valve; a pump comprising connected cylinders disposed one above the other, the upper cylinder being of greater diameter than the lower, the lower

cylinder being provided with an inlet check valve, there being a delivery connection provided with a return check valve for the lower end of the upper cylinder to the first tank; a plunger for the lower cylinder; a piston for the upper cylinder, there being means for delivering air below the piston on its upstroke, said piston and plunger being connected to move together, whereby on the upstroke water is lifted into the upper cylinder and air passes below its piston, and on the downstroke air and water are forced into the first tank; a second pump, there being a delivery connection for said second pump to the second tank provided with a return check valve; means for automatically controlling said return check in said connection; and a float controlled motor switch actuated to open when the water in the first tank is at a predetermined point.

5. In a structure of the class described, the combination of a pair of pressure storage tanks, the tops of the tanks being connected by an air passage, said tanks being provided with a pressure relief valve; a pump comprising connected cylinders disposed one above the other, the upper cylinder being of greater diameter than the lower, the lower cylinder being provided with an inlet check valve, the upper cylinder being provided with an air inlet valve and a vent cock at its upper end, there being a delivery connection provided with a return check valve for the lower end of the upper cylinder to the first tank; a plunger for the lower cylinder; a piston for the upper cylinder provided with a spring check valve permitting the passage of air below the piston on its upstroke, said piston and plunger being connected to move together, whereby on the upstroke water is lifted into the upper cylinder and air passes below its piston, and on the downstroke air and water are forced into the first tank; and a second pump, there being a delivery connection for said second pump to the second tank.

6. In a structure of the class described, the combination of a pair of pressure storage tanks, the tops of the tanks being connected by an air passage, said tanks being provided with a pressure relief valve; a pump comprising connected cylinders disposed one above the other, the upper cylinder being of greater diameter than the lower, the lower cylinder being provided with an inlet check valve, there being a delivery connection provided with a return check valve for the lower end of the upper cylinder to the first tank; a plunger for the lower cylinder; a piston for the upper cylinder, there being means for delivering air below the piston on its upstroke, said piston and plunger being connected to move together, whereby on the upstroke water is lifted into the upper cylinder and air passes

below its piston, and on the downstroke air and water are forced into the first tank; and a second pump, there being a delivery connection for said second pump to the second tank.

7. In a structure of the class described, the combination of a pair of pressure storage tanks, the tops of the tanks being connected by an air passage, said tanks being

10 provided with a relief valve; a pump adapted to deliver air and water to the first tank; a second pump, there being a return check valve and supply connections for the second pump and a delivery connection for said

15 second pump to the said second tank provided with a return check valve; an electro-magnet for holding said return check valve in said second tank connection in its open position; a float controlled switch for said

20 electro-magnet actuated to close when the water in the second tank is at a predetermined point; and a float controlled motor switch actuated to open when the water in the first tank is at a predetermined point.

25 8. In a structure of the class described, the combination of a pair of pressure storage tanks, the tops of the tanks being connected by an air passage, said tanks being provided with a relief valve; a pump adapted

30 to deliver air and water to the first tank; a second pump, there being a delivery connection for said second pump to the said second tank provided with a return check valve; means for automatically controlling

35 said return check in said connection; a driving motor for said pumps; and a float actuated control member.

9. In a structure of the class described, the combination of a pair of pressure storage

40 tanks, the tops of the tanks being connected by an air passage, said tanks being provided with a pressure relief valve; a pump adapted to deliver air and water to the first tank; a second pump, there being a delivery connection for said second pump to the second

45 tank provided with a return check valve; means for automatically controlling said return check in said connection, comprising a float in said second tank; and a float controlled motor switch actuated to open when the water in the first tank is at a predetermined point.

50 10. In a structure of the class described, the combination of a pair of pressure storage tanks, the tops of the tanks being connected by an air passage provided with a return check valve, the second tank being provided

55 with a pressure relief valve; a pump adapted to deliver air and water to the first tank; a second pump having a delivery connection to the second tank; means for controlling

60 said delivery connection; and a motor control actuated when the water in the first tank is at a predetermined point.

65 11. In a structure of the class described,

the combination with the well pipe, of a shaft support constituting a bottom frame member clamped upon said well pipe, the pipe constituting a frame support member; a pair of rear uprights arranged through 70 said shaft support member; a floor plate for said rear uprights; a pair of front uprights carried by said shaft support member; a top frame member connecting said front and rear uprights; a cross head mounted to reciprocate on the front pair of uprights; a crank wheel shaft and a driving wheel shaft carried by said shaft support member; a crank wheel at each side of said frame uprights mounted on said crank wheel shaft; 75 a centrally-disposed driving wheel mounted on said shaft support member, the driving wheel being provided with a belt pulley at each side; belts connecting said crank wheels with said driving wheel belt pulleys; pitmen 80 connecting said cross head to said crank wheels; and a motor support or bracket mounted on said uprights to support the motor with its fly wheel in alignment with said driving wheel.

90 12. In a structure of the class described, the combination with the well pipe, of a shaft support constituting a bottom frame member clamped upon said well pipe, the pipe constituting a frame support member; 95 a pair of rear uprights arranged through said shaft support member; a floor plate for said rear uprights; a pair of front uprights carried by said shaft support member; a top frame member connecting said front and rear uprights; a cross head mounted to reciprocate on the front pair of uprights; a crank wheel shaft and a driving wheel shaft carried by said shaft support member; a crank wheel at each side 100 of said frame uprights mounted on said crank wheel shaft; a centrally-disposed driving wheel mounted on said shaft support member and having driving connection to said crank wheels; pitmen connecting said 105 cross head to said crank wheels; and a motor support or bracket mounted on said uprights.

115 13. In a structure of the class described, the combination with the well pipe, of a frame comprising a shaft support member clamped upon said well pipe, and a pair of frame uprights; a cross head mounted to reciprocate on said uprights; a crank wheel shaft and a driving wheel shaft carried by 120 said shaft support member; a crank wheel at each side of said frame member; a centrally-disposed driving wheel mounted on said shaft support member, the driving wheel being provided with a belt pulley at each side; belts connecting said crank wheels with said driving wheel belt pulleys; and pitmen connecting said cross head to said 125 crank wheels.

14. In a structure of the class described, 130

the combination with the well pipe, of a frame comprising a shaft support member clamped upon said well pipe, and a pair of frame uprights; a cross head mounted to reciprocate on the front pair of uprights; a crank wheel shaft and a driving wheel shaft carried by said shaft support member; a crank wheel at each side of said frame member; a centrally-disposed driving wheel mounted on said shaft support member; a driving connection for said driving wheel to

said crank wheels; and pitmen connecting said cross head to said crank wheels.

In witness whereof, we have hereunto set our hands and seals in the presence of two ¹⁵ witnesses.
